HEM GUIDE CLASP

Wendy Weeks, Great Neck, N. Y.

Application June 27, 1947, Serial No. 757,604

1 Claim. (Cl. 24—81)

1

The present invention relates to a sewing accessory and it consists in the combinations, constructions and arrangements of parts herein described and claimed.

It is an object of the invention to provide a simple, inexpensive, efficient and effective sewing accessory.

Another object of the invention is the provision of a guide and clamp formed of a single piece of material.

A further object of the invention is the provision of a hem holder having indicia upon one side thereof whereby hems may be formed with accuracy and expediency.

A further object of the invention is the provision, in a device of the character set forth above, of novel clamping means for flexible material.

Other and further objects of the invention will become apparent from a reading of the following specification taken in conjunction with the drawing, in which:

Figure 1 is a perspective view of an embodiment of the invention, as used in one stage of the formation of a hem for a garment.

Figure 2 is a perspective view showing a plurality of the devices shown in Figure 1 as viewed from the reverse side and in another stage of the formation of the hem of a garment.

Figure 3 is a rear elevational view of the device shown in Figures 1 and 2.

Figure 4 is a side elevational view of Figure 3.

Figure 5 is a plan view of a blank used to form the embodiment of the invention shown in Figures 1 to 4, prior to bending the same into final shape.

Figures 6 and 7 are perspective views of modified forms the invention may assume, and

Figure 8 is a sectional view taken along line 8—8 of Figure 3.

Generally, the invention comprises a device which is adapted to be used in the formation of hems for garments and for other like uses. In the preferred embodiment of the invention, the device is formed of a single elongated piece of spring metal having its outer extremities folded against one side thereof to form a pair of spring clips. The ends are oppositely tapered and bent to form finger pieces for their easy manipulation, and a looped portion is provided at the point of bending whereby the folds of material to be clamped may be readily accommodated. In the preferred form the tapered formation of the outer ends of the blank allows for the extremities to extend beyond each other in the finished product. In one modification of the invention the extremi-

2

ties of the blank are provided with squared ends formed into finger grips which, however, merely extend to points adjacent each other and in another embodiment of the invention the blank is formed with a single fold providing a pair of identical front and rear portions having outwardly flared finger grips and providing a looped portion for the accommodation of the folds of fabric to be clamped therein.

10 Referring now more particularly to the drawing, there is shown therein, in Figure 5 an elongated blank 10 preferably formed of spring metal and having oppositely tapered extremities 11 and 12. Indicia 13 may be stamped into or otherwise placed upon one side of the blank which will hereinafter be called the face 14. In this form of the invention, the extremities 11 and 12 are bent rearwardly of the face 14 in such manner that the sides thereof remain parallel throughout and 20 in such manner as to form looped portions 15 and 16. The extremities 11 and 12, when thus bent, extend slightly beyond each other and are bent outwardly to form integral finger grips 17 and 18.

25 In using this embodiment of the invention for the formation, for example, of a hem for garments, reference may be had to Figure 1 wherein the extremities or clamp members 11 are shown as clamping the folded edge of a garment 19 in such manner that the folded portion 20 thereof lies upon the inner side of such garment and the clamp members 11 upon the outer side of said garment. In the next step in the formation 30 of a hem the folded portion 20 is again folded in the same direction, that is to say in this case, toward the outer portion of the garment, as indicated at 21 and is held by the extreme or clamp members 12 by a plurality of the devices under consideration.

35 It will be seen that the looped portions 16 of the devices accommodate the actual line of fold 22 of the fabric of the garment 19. When the hem has reached the stage of development shown in Figure 2 and is held in place by a plurality of the devices forming this invention, the width of the hem may then be accurately measured and made uniform throughout by reference to indicia 13 on the faces 14 of the devices. It 40 will be seen that the finger pieces 17 and 18 may be readily engaged by the finger tips of the user especially in view of the fact that the tapered construction of the extremities 11 and 12 provide additional spaces 23 and 24 for the approach of the user's fingers.

In the form of the invention shown in Figure 6, the construction is identical with that above described with the exception that the extremities 11 and 12 are provided with squared ends 25 and 26, respectively which ends are formed into finger grips 27 and 28, respectively. In use, the operation is identical with that heretofore described with reference to Figures 1 to 5, inclusive, and it will be understood that the face 14 likewise bears indicia in the manner above described.

Referring to the embodiment of the invention shown in Figure 7, the device is in this case formed of a single blank into a face portion 29 and a rear portion 30 of substantially identical form and each provided with an outwardly extending finger grip 31 and 32, respectively. A looped portion 33 is formed at the point of bending of this device and the face 29 is provided with indicia 13 as in the other forms of the invention. Again, in this form of the invention, the operation of the device for the formation of the hem of a garment or other like work in connection with the fabrication of garments and the like, is identical with that above described.

While but three forms the invention may assume have been shown and described herein, it will be readily apparent to those skilled in the art that many minor modifications may be made without departing from the spirit of the invention or the scope of the appended claim.

What is claimed is:

A device of the character described comprising a face portion, rear portions respectively integrally formed on the ends of the face portion and extending toward each other, said rear portions respectively being cut away along opposing side edges and providing tapered ends, said tapered ends overlapping one another in a single plane and having opposingly outwardly flared finger grips, the rear portions being substantially straight and extending parallel to the face portion, said outwardly flared finger grips being laterally aligned with each other.

WENDY WEEKS.
